Primary Examiner — George D Kirschbaum*Assistant Examiner* — Clese Moore, Jr.*(74) Attorney, Agent, or Firm* — Harness, Dickey & Pierce, P.L.C.(57) **CLAIM**

The ornamental design for an automobile control component, as shown and described.

DESCRIPTION

FIG. 1 is a perspective view of an automobile control component as a key;

FIG. 2 is a top plan view thereof;

FIG. 3 is a bottom plan view thereof;

FIG. 4 is a front elevational view thereof;

FIG. 5 is a rear elevational view thereof;

FIG. 6 is a right side elevational view thereof; and,

FIG. 7 is a left side elevational view thereof.
